(57) **CLAIM**

The ornamental design for a stringed musical instrument as shown and described.

DESCRIPTION

FIG. 1 is a front perspective view of a stringed musical instrument;

FIG. 2 is a front view of the stringed musical instrument;

FIG. 3 is a left side view of the stringed musical instrument;

FIG. 4 is a right side view of the stringed musical instrument;

FIG. 5 is an enlarged top view of the stringed musical instrument;

FIG. 6 is an enlarged bottom view of the stringed musical instrument;

FIG. 7 is a rear view of the stringed musical instrument; and,

FIG. 8 is a rear perspective view of the stringed musical instrument.

The broken lines of the stringed musical instrument are for the purpose of illustrating environmental structure and form no part of the claimed design.
